LADDER SIDE MEMBER EXTENSION
ATTACHMENT

Louis P. Noel and Hammond J. Griffin, Battle Creek, and Homer D. De Moss, Climax, Mich.; said Noel assignor to said Griffin and said De Moss

Application July 24, 1948, Serial No. 40,576

6 Claims. (Cl. 228—63)

1

The present invention relates broadly to ladders, and in its specific phases to adjustable means for extending either side piece of a ladder to permit same to stand substantially perpendicular on uneven or inclined surfaces.

Where ladders have had to be used on uneven or sidewise sloping ground, steps, and the like, it has been common practice to place blocks under the short side piece of the ladder to support it. This is a very dangerous procedure as is evidenced by the large number of accidents which result from falling ladders. In recognition of this bad situation, several devices have been proposed which permit lengthening one side piece of the ladder relative to the other so that same may stand upright on an uneven footing. The most of these devices have been built into the ladder so that the whole ladder assembly had to be carried at all times in order to meet the uneven footing situation. A very few of these devices were proposed as loose attachments for ladders, but they have apparently proved to be either unstable or so complex as to be commercially unfeasible. It was a recognition of the need of a detachable ladder extension leg assembly and the lack of same on the open market, as well as a knowledge of the difficulties and shortcomings of the prior practice, which lead to the conception and development of the present invention.

Accordingly among the objects of the present invention is the provision of an adjustable ladder extension leg assembly for use on the end of either side piece of a ladder, wherein such assembly is simple in construction, durable, easy to adjust, and highly efficient as a support for retaining a ladder in perpendicular position.

Another object is to provide a ladder extension leg assembly which can be applied to a ladder side piece without requiring alterations of any kind to the ladder structure.

Another object is to provide a detachable ladder extension leg assembly which is safe, easily anchored in place, and has a positive locking mechanism for fastening same in various adjusted positions.

A further object is to provide a ladder extension leg assembly which has a pocket with a closed end and slotted side for the reception of the end of a ladder side piece, and which is quickly mountable and dismountable from the ladder without the use of tools of any kind.

A further object is to provide a ladder extension leg assembly which is positively adjust-

able by predetermined amounts lengthwise of the side piece of the ladder.

Still further objects and advantages of the present invention will appear as the description proceeds.

To the accomplishment of the foregoing and related ends, the invention, then, consists of the means hereinafter fully described and particularly pointed out in the claims, the annexed drawing and the following description setting forth in detail certain means for carrying out the invention, such disclosed means illustrating, however, but one of various ways in which the principle of the invention may be used.

15 In the annexed drawing:

Figure 1 shows a front view of a ladder with a preferred form of the ladder extension leg assembly of the present invention mounted thereon.

Figure 2 shows a side view of the assembly illustrated in Figure 1.

Figure 3 shows a section view as taken at line 3—3 of Figure 1 looking in the direction of the arrows.

Figure 4 shows a section view as taken at line 4—4 of Figure 3 looking in the direction of the arrows.

Referring more particularly to Figure 1 of the drawing, it will be noted that the ladder 1 is mounted on stairs 2, which diagrammatically illustrate an uneven surface, wherein one side piece 3 of the ladder would normally be unsupported unless the conventional plan of putting blocks under same were followed. To overcome this a ladder extension leg assembly 4 is shown mounted in place on side piece 3 of the ladder where it is held in place by means of tension spring 5 which has a hook-end 6 engaging rung 7 of the ladder.

The ladder extension leg assembly 4 has a pocket 8 which has a closed bottom 9 and an open side slot 10 of a width slightly greater than the thickness of the ladder rungs 7 so that the rung will pass down the slot when the ladder extension leg is being mounted on a side piece of the ladder as is shown in Figure 1. Pocket member 8 is reinforced and stiffened at its ends and middle by means of three brace straps 11, 12, and 13 to which the pocket is anchored, for instance, by welding. The top and middle brace straps 11 and 12 are left open at slot 10 of pocket 8 so that rung 7 may pass therethrough.

Adapted to slidably fit within brace straps 11, 12, and 13, and behind pocket 8, is an extension leg member 14 which is preferably rectangular and which has on its outer face a reinforcing

metal strip 15 provided with closely spaced perforations 16. Metal strip 15 is conventionally fastened to leg 14, for instance, by means of screws 17.

Joined to the rear face of brace straps 11, 12, and 13 is a longitudinal brace strap 18. Fastened to longitudinal brace strap 18 at brace strap 12 is a longitudinally extending outwardly projecting substantially U-shaped support member 19. Support member 19, longitudinal brace strap 18, and circumferential brace strap 12 are perforated in alignment for the reception of a bolt action locking member 20 as shown more particularly in Figure 4. The point 21 of locking member 20 is preferably tapered for a short distance to facilitate entry into perforations 16, and the recesses 22 behind same, in extension leg member 14. The outer end of locking member 20 is preferably turned down as shown and a short pin 23 mounted to project in one direction from the side of the locking member just inside of support member 19 when member 20 is in locking position. This support member 19 is provided with a slot 24 extending from one side of the perforation so that when the outer end of locking member 20 is turned upward, pin 23 may be slid out through slot 24 to permit disengagement of point 21 from the perforations in the extension leg member 14 and perforated reinforcing metal strip 15. This allows the extension leg to be adjusted up and down as required to meet the particular unevenness of the surface on which the ladder is to be mounted. A pin 25, which may be of straight, taper, or cotter pin type, passes through locking member 20 at the point shown and extends from both sides of same. This pin prevents the locking member 20 from being fully withdrawn from support member 19 when the locking member is slid outward to permit adjustment of the extension leg member 14. By having pin 23 extend in the same direction as the outer end of locking member 20, gravity will normally hold the outer end of locking member 20 down and hence the assembly will be locked when pin 23 is in the position shown in Figure 4. This procedure, while being positive and safe, permits quick and easy adjustment of the assembly.

The ladder extension leg assembly is the same as a tool and can be carried by plumbers, carpenters, roofers, brick layers, and the like, in their service truck, since it is adaptable to be slipped onto any standard ladder for positive and safe use therewith. When a job involves uneven terrain, steps, or the like, where the ladder must be set up, and wherein one side piece of the ladder will not reach the surface below same, this ladder extension assembly may be slipped onto that side piece of the ladder, and the hook 6 of spring 5 hooked over the ladder rung to anchor the assembly together so that the ladder can be carried around without the ladder extension leg assembly falling off. The ladder carrying the extension leg assembly may then be set in place where it is to be used, following which locking member 20 may have its outer end turned up so that pin 23 will coincide with slot 24 whereupon locking member 20 may be moved outward and the ladder extension leg 14 moved endwise until it comes into suitable contact with the ground. Locking member 20 is then moved back through support member 19 with end 21 engaging one of the recesses 22, following which the outer end of locking member 20 may be turned down to positively anchor the assembly in adjusted position ready for use. At the end of the use period, hook 6

of spring 5 may be disengaged from ladder rung 7, and the ladder extension leg assembly 4 returned to the truck for transportation until required once more.

Other modes of applying the principle of our invention may be employed instead of the one explained, change being made as regards the apparatus herein disclosed, provided the means stated by any of the following claims or the equivalent of such stated means be employed.

We therefore particularly point out and distinctly claim as our invention:

1. A slip-on, detachable, extension leg assembly for a ladder having side members and rungs, which comprises a substantially tubular pocket of suitable size to receive and hold the end of a side member of said ladder, said pocket having a slot in one side for the passage of a ladder rung therethrough and a bottom means for supporting the end of said ladder side member, an endwise adjustable leg member, top and bottom reinforcing means for said pocket, means for fastening said reinforcing means to said pocket, each of said top and bottom reinforcing means having a portion extending sidewise from said pocket for holding and guiding said leg member for lengthwise movement along the side of said pocket, a locking assembly joined to said pocket in fixed location, said locking assembly including a locking member adapted to be moved toward said pocket to engage and hold said adjustable leg member, and means for releasably holding said locking member in locking engagement with said adjustable leg member.
2. A slip-on, detachable, extension leg assembly for a ladder having side members and rungs, which comprises a substantially tubular pocket of suitable size to receive and hold the end of a side member of said ladder, said pocket having a slot in one side for the passage of a ladder rung therethrough and a bottom means for supporting the end of said ladder side member, an endwise adjustable leg member, top and bottom reinforcing means for said pocket, means for fastening said reinforcing means to said pocket, each of said top and bottom reinforcing means having an extending and encircling portion for holding and guiding said leg member for lengthwise movement along the side of said pocket, said leg member having engageable means on its outer face, a locking assembly joined to said pocket in fixed location, said locking assembly including a bolt action locking member adapted to be moved toward said pocket to engage said engageable means on the outer face of said adjustable leg and hold same against endwise movement, and means for releasably holding said locking member in positive locking engagement with said adjustable leg member.
3. A slip-on, detachable, extension leg assembly for a ladder having side members and rungs, which comprises a pocket of suitable size to receive the end of a side member of said ladder, said pocket having a bottom means for supporting the end of said side member, an endwise adjustable leg member, top and bottom reinforcing means for said pocket, means for fastening said reinforcing means to said pocket, each of said top and bottom reinforcing means having an extending and encircling portion for holding and guiding said leg member for lengthwise movement along the side of said pocket, a longitudinal brace strap joining the outer face of said top and bottom reinforcing means, said leg member having engageable means on its outer

5

face, a U-shaped support member with the legs of said U-shaped member attached to the outer face of said longitudinal brace strap, said brace strap and U-shaped member being cross drilled in alignment, a bolt action locking member adapted to be moved through said aligned openings toward said pocket to engage said engageable means on the outer face of said adjustable leg and hold same against endwise movement, and projecting means on said locking member which cooperates with said U-shaped member for releasably holding said locking member in locking engagement with said adjustable leg member.

4. A slip-on, detachable, extension leg assembly for a ladder having side members and rungs, which comprise a pocket of suitable size to receive the end of a side member of said ladder, said pocket having a bottom means for supporting the end of said side member, an endwise adjustable leg member, top, intermediate, and bottom reinforcing means for said pocket, means for fastening said reinforcing means to said pocket, each of said top, intermediate, and bottom reinforcing means having an extending and encircling portion for holding and guiding said leg member for lengthwise movement along the side of said pocket, a longitudinal brace strap joining the outer face of said top, intermediate, and bottom reinforcing means, said leg member having engageable means on its outer face, a U-shaped support member with the legs of said U-shaped member attached to the outer face of said longitudinal brace strap, said intermediate reinforcing means, brace strap, and U-shaped member being cross drilled in alignment, a bolt action locking member adapted to be moved through said aligned openings toward said pocket to engage said engageable means on the outer face of said adjustable leg and hold same against endwise movement, means in the form of a pin projecting sidewise from said locking member and cooperating with a sidewise extending slot portion of said opening through said U-shaped member for releasably holding said locking member in locking engagement with said adjustable leg member and yet permitting same to be disengaged, and an adjustable hook-ended releasable anchor means for holding said pocket on said ladder with one of its side members therein.

5. A slip-on, detachable, extension leg assembly for a ladder having side members and rungs, which comprises a pocket of suitable size to receive the end of a side member of said ladder, said pocket having an open side slot into which a rung of said ladder may pass, said pocket also having a closed bottom for supporting the end of said side member, a substantially rectangular section endwise adjustable leg member, top and bottom reinforcing means for said pocket, each of said top and bottom reinforcing means having an extending and encircling portion for holding and guiding said leg member lengthwise of the side of said pocket, said top reinforcing means being open ended so as to allow a rung of said ladder to pass therethrough and down the slot of said pocket, a longitudinal brace strap joining the outer face of said top and bottom reinforcing means, said leg member having an aligned row of relatively closely spaced recesses extending inward from the outer face of same, a U-shaped support member with the legs of said U-shaped member attached to the outer face of said longitudinal brace strap, said brace strap and U-

6

shaped member being cross drilled in alignment with the recesses in said leg member, a locking member, said locking member being in the form of a substantially round rod adapted to fit the aligned openings in said brace strap and U-shaped member and having a point adapted to fit the recesses in said leg member, the outer end of said locking member being turned downward to form a handle just outside of said U-shaped member when the point of said locking member is in engagement with a recess of said leg member, a short pin extending from one side of said locking member just inside of said U-shaped member when said locking member is in engagement with said leg member, said U-shaped member having a slot extending from one side of the perforation therethrough, said slot being of a size to allow said pin to pass therethrough when said locking member is rotated to unlocking position, and gripping means for holding said pocket on said ladder with one of the side members of the latter therein.

6. A slip-on, detachable, extension leg assembly for a ladder having side members and rungs, which comprises a pocket of suitable size to receive the end of a side member of said ladder, said pocket having an open side slot into which a rung of said ladder may pass, said pocket also having a closed bottom for supporting the end of said side member, a substantially rectangular section endwise adjustable leg member, top and bottom reinforcing means for said pocket, each of said top and bottom reinforcing means having an extending and encircling portion for holding and guiding said leg member lengthwise of the side of said pocket, said top reinforcing means open ended so as to allow a rung of said ladder to pass therethrough and down the slot of said pocket, a longitudinal brace strap joining the outer face of said top and bottom reinforcing means, said leg member having an aligned row of relatively closely spaced recesses extending inward from the outer face of same, a reinforcing metal strip on the outer face of said leg member, said strip being correspondingly perforated in alignment with the recesses in said leg member, a U-shaped support member with the legs of said U-shaped member attached to the outer face of said longitudinal brace strap intermediate its ends, said brace strap and U-shaped member being cross drilled in alignment with the recesses in said leg member, a locking member, said locking member being in the form of a substantially round rod adapted to fit the aligned openings in said brace strap and U-shaped member and having a point adapted to fit the recesses in said leg member, the outer end of said locking member being turned downward to form a handle just outside of said U-shaped member when the point of said locking member is in engagement with a recess of said leg member, a short pin extending from one side of said locking member substantially parallel to the turned down portion thereof and just inside of said U-shaped member when said locking member is in engagement with said leg member, said U-shaped member having a slot extending from one side of the perforation therethrough, said slot being of a size to allow said pin to pass therethrough when the turned down portion of said locking member is rotated up to unlocking position, a short pin passing through said locking member and projecting from both sides thereof, said pin being adjacent the outer face of said

longitudinal brace strap when said locking member is locked in engagement with a recess of said leg, said pin also acting as a stop for said locking member when the latter is moved to unlock position, and a tension spring fastened at one end to said pocket including assembly, the other end of said spring having a hook adapted for hooking over a rung of said ladder to hold the assembly firmly in place.
